UNITED STATES PATENT OFFICE.

HARRY J. HUFFORD, OF SCRANTON, PENNSYLVANIA.

THREAD-GUIDING MEANS.

Application filed October 18, 1928. Serial No. 313,341.

Spooling and analogous machines are provided with thread cleaners and with thread-guiding eyes usually disposed above and below said cleaners. More or less unscrupulous attendants are in the great majority of cases employed for operating such machines and they are paid according to their daily output. This output is much greater if the thread is not engaged at all with the thread cleaner and hence it is quite common to find the thread running along the outer side of the cleaner body instead of between the thread-cleaning blades. When this is discovered, the attendant merely conjectures that the thread jumped out of the cleaner and places it back, and there is no evidence to the contrary. It is the object of my invention however to provide new and improved thread-guiding means easily threaded at a single operation with passing the thread between the cleaner blades, when said thread is held taut at two vertically spaced points and rearwardly moved in a vertical plane. Movement of the thread in this manner cannot fail to pass it between the cleaner blades and the guiding means is so constructed that if the thread be moved in some other plane, in an attempt to thread the guides without engaging the thread with the cleaner, said thread cannot move fully into said eyes without special manipulation of said thread. Hence, whenever the thread is found passing around the thread cleaner but fully engaged with the guide eyes, it is known that the attendant deliberately threaded said eyes but not the cleaner, it being assumed of course that the cleaner blades are sufficiently long so that there is no possibility of the thread jumping out from the space between them. Hence, anyone guilty of passing the thread around the cleaner instead of through it for her own benefit, can be easily detected and proper steps taken.

With the foregoing in view, the invention resides in the novel subject matter herein-after described and claimed, description being accomplished by reference to the accompanying drawings.

Fig. 1 is a perspective view of an assemblage embodying a thread cleaner and two of the improved eyes disposed respectively above and below the same.

Fig. 2 is a top plan view of one of the eyes.

Fig. 3 is a side elevation.

Fig. 4 is a bottom plan view.

Fig. 5 is a vertical transverse section on the plane indicated by the lines 5—5 of Figs. 2, 3 and 4.

Fig. 6 is a front elevation of the assemblage shown in Fig. 1 illustrating the thread in two inclined planes and contacting with the edges of the cleaner instead of being engaged with it. When rearwardly moved in either of these planes, the thread cannot be fully engaged with the guiding means at a single operation, for reasons hereinafter described.

In the drawings above briefly described, S denotes an appropriate support to be secured to the frame of the machine by fasteners passed through openings O. The support S is provided with a horizontal forwardly projecting portion H carrying two thread scraping blades b having closely spaced parallel inner edges for engagement with the thread T. Secured to and projecting forwardly from the support S, respectively above and below the blades b, are two thread-guiding eyes G, each embodying a head 7 at the front end of an attaching shank 7^a. As the constructions of both guides are identical, only one will be described in detail, and it may here be explained that in so describing the guide and in claiming it, such terms as "front", "rear", "vertical", "upper", "lower", "below", and "downwardly", are to be considered as relative rather than limiting, as the eye could obviously be used in various positions. Without definite terms however, a clear explanation could not be given, and hence such expression as those enumerated, have been adopted.

The head 7 embodies a relatively long forwardly projecting arm 8 and a comparatively short forwardly projecting arm 9, the two arms being closely spaced to receive the thread therebetween and extending in a horizontal direction. The inner side of the arm 8 is transversely curved convexedly as shown at 10 in Fig. 5, and at its front end, said inner side is curved outwardly as at 11. The relatively short arm 9 is downwardly widened as indicated at 12 and the downwardly projecting portion of this arm is provided with a rearwardly directed finger 13 which is spaced slightly from the inner vertical side 14 of said arm 9, said finger acting as a guard to prevent the thread from lashing out of the space 15 between the rear ends of the arms 8—9. The outer sides 16—17 of the

arm portion 12 and the finger 13 are convexedly curved as seen in Figs. 5 and 6, and these sides are also longitudinally curved as seen in Figs. 2 and 4, the longitudinal curvatures meeting each other at a nose 18 shown in a number of the views. The upper side 20 of the finger 13 is transversely curved and merges gradually into the inner side 14 of the arm 9, and said side 20 is spaced slightly from the curved inner side 10 of the arm 8 to permit passage of thread between the two.

When the thread T is held taut between two points A—B and is rearwardly moved 15 in a vertical plane, it may be at a single operation passed between the cleaner blades b and engaged with both of the eyes G. When moving the thread in this manner, it comes in contact with the curved portion 11 20 of the arm 8 and the curved portion 17 of the finger 13 as will be clear by reference to the arrow 21 of Fig. 2. Then, as the thread is moved rearwardly, it follows along the curved inner side 10 of the arm 8 and the 25 curved outer side 17 of the finger 13 and eventually snaps behind the latter into the space 15. This same travel of thread takes place in connection with the upper and lower guide G and simultaneously with threading 30 of these eyes in this manner, the thread is engaged with the blades b of the thread cleaner. If an attendant attempts to thread either or both of the guides G without engaging the thread with the cleaning blades b, she is prevented from doing so at a single 35 operation but must necessarily manipulate the thread to fully engage it with the guide or guides. If the thread is held taut between two points A'—B' (Fig. 6) and moved rear- 40 wardly in an inclined plane, it can enter between the finger 13 and the arm 8 and be received in the space 15. However, the thread cannot then snap behind the finger 13 and become fully engaged with the guide. 45 Hence, if the thread is found running around the thread cleaner and fully engaged with the eye, it is known absolutely that it was deliberately threaded in this manner. In this connection, considering the thread 50 held between the points A'—B' of Fig. 6, it will be obvious that by exerting inward and rearward pressure on the thread as indicated by the arrow 22, it could be engaged fully with the eye, but only in this manner can this 55 full engagement of thread and eye be effected. Hence, if the thread be found running around the cleaner but still fully engaged with the eye, it is known that the attendant went through this special manipulation of the thread to deliberately engage it with the eye and not with the cleaner.

If the thread be tightly held between the two points A'—B' of Fig. 6 and rearwardly moved in an inclined plane, attempting to 60 thread the eye without threading the clean-

er, said thread will come in contact either with the curved portions 11—16 or with the curved portion 17 and will consequently be deflected without entering the eye at all. Hence, if the thread be found fully engaged 70 with the eye and running across the right-hand side of the cleaner, it is again known that said thread was deliberately threaded in this manner.

The immediately preceding description 75 has been given only in connection with the uppermost of the guide eyes G but the same difficulties are encountered in attempting to thread the lower eye without at the same time threading the cleaner. The attendant 80 may at a single operation thread both eyes and the cleaner, as intended but if she be unscrupulous, pass the thread around the cleaner and engage it by manipulation with the eyes, it is known that this was not accidental 85 and adequate steps may be taken to see that there is no repetition of such practice.

I claim:—

1. In an assemblage of the class described, a rigidly mounted thread cleaner having 90 spaced opposed scraping edges, and a rigidly mounted eye spaced from said cleaner, said eye embodying a guide into which the thread may be fully passed at a single operation when held taut and rearwardly moved in a plane between said edges, and means barring complete insertion of the thread into said guide at a single operation if held taut and rearwardly moved in another plane in an attempt to thread said eye without threading 95 said cleaner. 100

2. A thread guiding eye comprising a head embodying two forwardly projecting horizontal arms in close relation with each other to receive thread therebetween, one of said arms being downwardly widened and having on its lower portion a rearwardly turned finger spaced slightly from its inner side, said finger being also spaced slightly below the lower side of the other of said arms. 105

3. A thread guiding eye comprising a head embodying a relatively long horizontal arm and a comparatively short horizontal arm both projecting forwardly in close relation with each other to receive thread there- 110 between, the inner side of the longer arm being convexedly curved transversely and curved outwardly at its front end; said com- 115 paratively short arm being downwardly widened and having on its lower portion a rearwardly projecting finger spaced slightly from its inner side, the upper side of said finger merging gradually into said inner side and being spaced slightly below said long arm, the outer sides of said short arm and finger being curved inwardly and meeting 120 each other at their front ends.

In testimony whereof I have hereunto affixed my signature.

HARRY J. HUFFORD.
